UNITED STATES PATENT OFFICE.

HENRY AIKEN, OF PITTSBURG, PENNSYLVANIA.

TRUCK SIDE FRAME.

No. 877,280.

Specification of Letters Patent.

Patented Jan. 21, 1908.

Application filed October 24, 1907. Serial No. 398,874.

To all whom it may concern:

Be it known that I, HENRY AIKEN, of Pittsburgh, in the county of Allegheny, State of Pennsylvania, have invented a new and useful Truck Side Frame, of which the following is a full, clear, and exact description, reference being had to the accompanying drawings, forming part of this specification, in which—

10 Figure 1 is a top plan view of my improved side frame; Fig. 2 is a side elevation of the same partly broken away; Fig. 3 is a central cross section, and Fig. 4 is a cross section in the journal box portion.

15 My invention relates to the class of side frames for vehicle trucks, and is designed to provide a simple, cheap and strong construction therefor. To that end, it consists in securing the structural members together by 20 casting metal around or through them to form a part of the structure.

It further consists in applying this fluid metal to the end portion of the side frame, also in forming the central part of the side 25 frame by a casting which is welded or secured to the structural members by the casting operation.

It also consists in casting the journal box in contact with and thereby securing it to the 30 end portion of the frame.

In the drawings, in which I show the invention as applied to an ordinary arch bar truck frame, 2 represents the upper arch bar, 3 the lower arch bar and 4 the tie bar. In 35 the form shown, the lower arch bar extends outwardly beyond the end 5 of the upper arch bar, this end 6 of the lower arch bar being preferably bent upwardly, as shown in dotted lines, Fig. 2. The end portion of the tie bar

40 is preferably perforated, as indicated at 7. These end parts are then placed in a suitable mold and the journal box 8 is cast about them. The metal forming the lower part of the floor of the journal box flows through the 45 hole or notch of the tie bar, thus securing it firmly in place, while the journal box mold is preferably arranged to form an upward extension 9 of the cast metal which surrounds and incloses the end portions of the two arch bars. This fluid metal will flow into the gap 50 between the end 5 and the bent-up portion 6, and firmly secure these parts. The journal box may otherwise be of any ordinary or desirable type, so long as the fluid metal 55 flows around and secures the structural members of the frame in place.

To form the central portion of the side frame, including the truck columns, I also preferably form this central portion in one casting of general rectangular shape, as 60 shown at 10. The upper leg of this casting preferably surrounds and incloses the central horizontal portion 11 of the upper arch bar, while its lower leg portion similarly surrounds and incloses the central portions of 65 the lower arch bar and the tie bar. This lower leg of the casting is also preferably provided with perforated side lugs 12, to form a securing means for the spring plank or other portion. The side portions of this casting 70 may be provided with recesses or holes to lessen its weight.

The advantages of my invention will be apparent to those skilled in the art. The use of bolts, rivets or other securing means may 75 be done away with and a very strong structure afforded. The castings are preferably of steel, and in the act of forming them, the other parts of the frame are secured and strengthened, while the cast part is given its 80 desired shape. The journal boxes are secured to the frame at the same time that they are cast, thus doing away with additional securing means and with the labor and expense incident thereto. The center casting 85 is secured to the other members at the time of forming it, thus avoiding the use of securing means at these points.

The form and arrangement of the side frame may be varied. The casting securing 90 the ends of the arch bars may be formed separately from the journal box, if desired, so that a separate journal box may be applied; and many other changes may be made without departing from my invention. 95

I claim:

1. A truck frame having side frame members secured at their outer ends by a casting formed of fluid metal cast about the parts, substantially as described. 100
2. A truck side frame having a central or intermediate casting secured to the frame parts by flowing the metal about them, substantially as described. 105
3. A rivetless and boltless side frame having its parts secured by castings formed in place about them substantially as described. 110
4. A truck side frame having journal boxes cast in place with a part of the casting surrounding the side frame members, substantially as described.
5. An arch bar side frame having the arch

bars secured at their outer ends by a casting formed about them, substantially as described.

6. An arch bar side frame having the arch bars and tie bar secured by casting portions of a journal box about them, substantially as described.

7. An arch bar side frame having the arch bar members secured together by casting part of a journal box about them, substantially as described.

8. An arch bar side frame having the intermediate and end portions of the arch bars secured together by castings, substantially as described.

9. An arch bar side frame having the arch bars secured together at the ends by journal

boxes cast thereon and at the center by a casting secured thereto by flowing the casting about the arch bars, substantially as described.

10. An arch bar side frame having the arch bars and tie bar secured at the ends by casting portions of a journal box about them, said bars being secured at the intermediate part by another casting having parts surrounding them, substantially as described.

In testimony whereof, I have hereunto set my hand.

HENRY AIKEN.
